PNEUMATIC THREAD HOLDER FOR WEFT
REPLENISHING LOOMSRaymond F. Dion, Leominster, Mass., assignor to
Crompton & Knowles Loom Works, Worcester,
Mass., a corporation of Massachusetts

Application January 10, 1952, Serial No. 265,806

10 Claims. (Cl. 139—247)

1 This invention relates to thread holders for weft ends extending from bobbins in the magazine of a weft replenishing loom and it is the general object of the invention to provide a pneumatic thread holder of simple construction made in such manner that the weft ends can be readily threaded into it.

Weft replenishing looms of the bobbin changing type ordinarily employ some form of magazine holding reserve bobbins provided with weft ends or threads which extend to a thread holder. The thread holder is for the purpose of holding the threads taut so that they will be above the lay and not be broken by the latter, and also for the purpose of assisting the self-threading operation of the shuttle on the first pick of the shuttle after a bobbin changing operation. Furthermore, it is desirable where possible to have the thread holder so constructed that it will remove the thread of a freshly transferred bobbin when the thread is cut at the selvage on some beat of the loom subsequent to that on which weft replenishment occurs.

In a type of magazine which has gone into general use on multicolor weft replenishing looms the bobbins are arranged in vertical stacks and the threads from the bobbins extend downwardly at different angles toward the thread holder. It is an important object of the present invention to provide a pneumatic thread holder so constructed that it has a thread passage through which the weft ends of the highest bobbins in the magazine may pass in a more or less straight line to facilitate their entry into the thread passage. In this connection it is a further object of the invention to provide the aforesaid passage with an intake mouth the top of which will be spaced above the weft end extending from the highest bobbin in the magazine.

It is a further object of the invention to provide a pneumatic thread holder with a baffle or deflector adjacent to the discharge end of the thread passage located to break the force of the jet of air passing through the passage and provided with a thread slot by means of which the weft ends can be introduced into the thread passage. This feature of the invention contemplates a deflector curved outwardly and downwardly and the thread slot will extend throughout the length of the baffle and be continuous with a thread slot formed in the thread holder above the air and thread passage.

The invention to be set forth hereinafter is somewhat similar to that shown in my copending application Serial No. 261,867, filed December 15,

2 1951, but the present invention represents certain improvements over the thread holder shown in that application.

In order that the invention may be clearly understood reference is made to the accompanying drawings which illustrate by way of example the embodiments of the invention and in which:

Fig. 1 is a front elevation of part of a bobbin changing weft replenishing loom having the invention applied thereto,

Fig. 2 is an enlarged plan view looking in the direction of arrow 2, Fig. 1,

Fig. 3 is a vertical section on line 3—3, Fig. 2,
Fig. 4 is a vertical section on line 4—4, Fig. 3,
Fig. 5 is a detailed horizontal section on line 5—5, Fig. 3,

Fig. 6 is a diagrammatic plan view of the magazine and thread holder showing two groups of weft ends leading from bobbins in the magazine to the thread holder, and

Fig. 7 is a diagrammatic plan view of the thread holder illustrating the manner in which a weft end can be introduced into the thread holder.

Referring particularly to Fig. 1, the loom frame 1 is provided with a lay 2 which is reciprocated backwardly and forwardly in usual manner and operates with a shuttle S which is actuated by picking mechanism 3. When the invention is applied to a multicolor weft replenishing loom the shuttle shown in Fig. 1 will be only one of two or more shuttles which will ordinarily be in action one at a time.

The loom supports a magazine M having reserve bobbins from which weft ends extend to a thread holder designated herein generally at H. The particular magazine illustrated is of known type in which the reserve bobbins are held in vertical stacks, four stacks being illustrated in Fig. 6. Fresh bobbins are inserted into the magazine at the top thereof and the bobbins feed downwardly by gravity as bobbin changing operations remove the low bobbins in the magazine. The weft ends are arranged in front and back groups W1 and W2, respectively, see Fig. 6, group W1 leading from forward bobbin stacks B1 and B2, and group W2 leading from rear stacks B3 and B4. The magazine includes in its construction a tie rod 4 to which a downwardly and outwardly extending arm 5 is secured.

Except for the thread holder the matter thus far described may be of usual construction and operate in ordinary manner.

A support 6 is secured by bolt 7 to arm 5 and has a forwardly extending arm 8 on which is mounted a carrier 9 of inverted U-shaped form

as shown in Fig. 3. The carrier may be made of sheet metal and has vertical arms 10 and 11 through which extends a bolt 12 by means of which the carrier is secured to the arm 8. Mounted on top of the carrier is a hollow thread holder member 15 having a floor or base 16 which is secured to the carrier in any approved manner, as by welding. Member 15, which may be made of metal tubing, has a top 17 and front and back side walls 18 and 19, respectively, see Fig. 4.

The base, top and side walls of member 15 define an air and thread passage 20 which extends generally in a horizontal direction toward and from the magazine as will be apparent from Fig. 1, and intermediate the front stacks B1 and B2 and the rear stacks B3 and B4, see Fig. 6. The passage has an intake mouth 21 adjacent to the magazine and a discharge mouth 22 at the end thereof remote from the magazine. The top 17 is provided with a longitudinally extending thread slot 25 which opens downwardly into passage 20 and has its left end as viewed in Fig. 2 opening into the upper end of the intake mouth 21.

An injector tube T is supported by the arms 10 and 11 and has a discharge mouth 26 which as shown in Fig. 4 is elongated vertically and is located intermediate the front and back walls 18 and 19. The tube T is pneumatically connected to a hose or the like 27 which is connected to a source of compressed air (not shown) operating during the running of the loom to cause a jet or stream of air to issue from the mouth 26 in a direction away from the magazine and through the passage 20 between the walls 18 and 19 and the two groups W1 and W2 of weft ends in the passage 20 to hold the weft ends taut and to remove any weft end when it is cut at the cloth selvage subsequent to a bobbin changing operation.

Much of the matter thus far described has been set for the purpose of understanding the present invention and is similar to the thread holder shown in the aforesaid copending application, and is not claimed herein.

The present invention has more particular reference to the intake mouth 21 and an air and thread baffle or deflector. As shown in Figs. 2 and 3, the intake mouth is defined at its bottom by the base 16 and at its top by an edge 30 formed in that end of the top 17 of the member 15 adjacent to the magazine. The intake mouth is also defined by front and back side edges 31 and 32, respectively, which are inclined downwardly and toward the injector or magazine so that the edge 30 is farther from the magazine than the base 16. The right end of the base 16 as viewed in Fig. 3 is provided with an edge 35 over which the weft ends W1 and W2 can hang.

The top and bottom edges 30 and 35, respectively, are so located that the weft end of the highest bobbin in the magazine when drawn taut over the lower edge 35 will be spaced below the upper edge 30. This relationship is shown in Fig. 3 from which it will be apparent that there is a considerable open space 36 at the upper part of the intake mouth 21 above the highest of the weft ends located beyond the injector with reference to the magazine. In certain threading operations of the thread holder it may be convenient to place the weft ends of bobbins freshly inserted into the upper part of the magazine across this open space 36 so that the threads can be drawn into the passage 20 due to the jet of air issuing from the discharge mouth 26.

The hollow member 15 has secured thereto a baffle or deflector designated generally at 40 formed by front and back walls 41 and 42, respectively, secured in any approved manner to the top 17 of the member 15. The walls 41 and 42 are spaced from each other to define a thread slot 43 which in effect is a continuation of the thread slot 25. As shown more particularly in Figs. 1 and 3 the baffle or deflector 40 is curved outwardly and downwardly so that its lower end 44 is spaced from the discharge mouth 22. As shown for instance in Figs. 2 and 3 the rear wall 42 has the lower part thereof located slightly farther from the discharge mouth than the lower end of the front wall 41. The baffle 40 is so located that it breaks the force of the jet of air passing through the passage 20 to the right as viewed in Fig. 3 and enables the weft ends to fall over the edge 35 to form an entangled mass as shown for instance at G.

The threading operation is illustrated diagrammatically in Fig. 7, where it is assumed that a weft end or thread W extends from a bobbin freshly placed in high position in the rear part of the magazine. This thread W will be drawn to the right as viewed in Fig. 1 over the front wall 41 down along the latter as shown by the light line a, Fig. 7. The operator will then slide thread W rearwardly along wall 41 toward the rear wall 42 until the thread enters the lower part of the thread slot 43, as shown in the heavy line b, Fig. 7, and indicated in dotted lines in Fig. 5. After the thread has entered the slot 43 a downward force exerted on it by the operator will cause it to slide along the aligned slots 43 and 25 toward the magazine. When the thread is at the edge 30 and is held taut it will still be above the lower edge 35 so that it can be given an additional downward motion which will move it away from and to a position below the upper edge 30, thereby permitting it to enter the thread passage 20 without requiring any further manipulation. When the thread W is in passage 20 the jet of air will tend to move it toward rear wall 19 and it will assume the position shown at c in dotted lines, Fig. 7.

If the thread W had corresponded to a bobbin which had been placed in the front part of the magazine the threading operation would be as already described except that when the thread reached the passage 20 the jet of air would tend to blow it against the front wall 18. In either case the jet of air blows the thread against one or the other of the walls 41 or 42 of the baffle or deflector 40 to direct the thread downwardly. Thus, any thread corresponding to group W1 will be blown against the front wall 41 and any thread corresponding to group W2 will be blown against the rear wall 42. In both cases the threads will be deflected downwardly so that they will fall on their corresponding parts of the lower edge 35. This is due to the fact that the deflector is curved downwardly as distinguished from the forward curvature of the deflector shown in the aforesaid copending application.

From the foregoing it will be seen that the invention sets forth a simple form of pneumatic thread holder made in such manner that the thread of the highest bobbin in the magazine when held against lower edge 35 will be below the top edge 30. It will also be seen that a space 36 is located between the top weft ends entering the intake mouth 21 and the edge 30 to provide for entry of weft ends from bobbins freshly inserted in the magazine if this method of

threading the thread holder is desired. Also, the baffle or deflector 40 is curved downwardly and the walls 41 and 42 are aligned respectively with the groups W1 and W2 to direct the threads of these groups downwardly against their respective parts of the lower edge 35. Furthermore, the deflector is provided with a thread slot 43 which is a continuation of the thread slot 25. The lower part of one of the deflector walls, wall 42 as shown herein, is spaced slightly farther from the discharge mouth 22 than the lower part of forward wall 41 to facilitate entry of a thread in the slot 43 when the thread is slid rearwardly along the front wall 41. While wall 42 has been shown farther from the discharge mouth than wall 41 it will be understood that the relative positions of these walls can be reversed in which event the threading operation will be effected by sliding the thread forwardly along wall 42 toward wall 41.

Having now particularly described and ascertained the nature of the invention and in what manner the same is to be performed, what is claimed is:

1. In pneumatic thread holder means for a weft replenishing loom having a magazine to hold vertically arranged reserve bobbins from which weft ends extend, means defining an air and thread passage to receive said weft ends extending generally in a horizontal direction toward and from the magazine and having an intake mouth at the end thereof adjacent to the magazine formed with an upper edge and having a discharge mouth at the end thereof remote from the magazine formed with a lower edge, and an air injector to introduce a jet of compressed air into said intake mouth in a direction toward the discharge mouth to tension the weft ends in the passage, said upper and lower edges being so related to the topmost bobbin in the magazine that the weft end of said topmost bobbin when drawn taut over said edge enters the intake mouth at a point spaced below said upper edge.

2. The pneumatic thread holder set forth in claim 1 wherein said intake mouth is formed with side edges which are inclined from said upper edge downwardly and toward the injector to define a space above the weft ends below said upper edge beyond said injector with reference to the magazine to receive weft ends from bobbins in the magazine.

3. The pneumatic thread holder set forth in claim 1 wherein a deflector is located in the path of said jet of compressed air and beyond said discharge mouth with reference to the intake mouth and extends downwardly and outwardly from said discharge mouth to break the force of said jet of air and enable the weft ends issuing from the discharge mouth to hang down over said lower edge.

4. The pneumatic thread holder set forth in claim 3 wherein said deflector is supported from a part of said means above said discharge mouth.

5. The pneumatic thread holder set forth in claim 3 wherein said means and deflector are provided with a continuous thread slot extending lengthwise of said passage and open at the ends thereof through which weft ends may be introduced into said passage.

10. The pneumatic thread holder set forth in claim 5 wherein said deflector has a free lower end spaced from said discharge mouth and said thread slot extends from said upper edge to the lower end of said deflector.

15. The pneumatic thread holder set forth in claim 6 wherein the free lower end of said deflector includes two spaced walls between which said thread slot extends and one of said walls is spaced farther from the discharge mouth than the other wall to enable a weft end on said other wall to enter said thread slot by horizontal movement when moved toward said one wall of the deflector.

20. The pneumatic thread holder means for a weft replenishing loom having a magazine to hold vertically arranged reserve bobbins from which front and back groups of weft ends extend, means defining an air and thread passage extending generally in a horizontal direction toward and from the magazine intermediate said groups of weft ends to receive the latter, an air injector to introduce a jet of compressed air into said passage between said groups in a direction away from the magazine, and a deflector beyond said passage with reference to the magazine extending downwardly and effective to break the force of the jet of air to enable said groups of weft ends to fall to their respective parts of the lower end of the passage adjacent to the deflector.

25. The pneumatic thread holder means set forth in claim 8 wherein the deflector includes two walls curved downwardly and in the direction of flow of air through said passage, one of said walls being aligned with one of said groups of weft ends and the other wall being aligned with the other group.

30. The pneumatic thread holder set forth in claim 9 wherein the means and deflector are provided with communicating thread slots and the thread slot in the deflector separates said walls.
